UNITED STATES PATENT OFFICE

PHILIP L. DAVIS AND JULIAN J. RAPHAEL, OF NEW YORK, N. Y., ASSIGNORS TO KEY-STONE TRANSPORTATION COMPANY, INC., OF NEW YORK, N. Y.

DESIGN FOR AN AUTOMOBILE VISOR RATE SIGN OR ARTICLE OF SIMILAR NATURE

Application filed December 22, 1930. Serial No. 38,090. Term of patent 14 years.

To all whom it may concern:

Be it known that we, PHILIP L. DAVIS, a citizen of the United States, residing in New York, in the county and State of New York, and JULIAN J. RAPHAEL, a citizen of the United States, residing in New York, in the county and State of New York, have invented a new, original, and ornamental Design for an Automobile Visor Rate Sign or Article of Similar Nature, of which the following is a specification, reference being had to the accompanying drawing, forming a part thereof.

Figure 1 is a side elevational view of an

automobile visor rate sign showing our new design.

Fig. 2 is a front elevational view thereof.

Fig. 3 is a top plan view thereof.

Fig. 4 is a perspective view thereof.

We claim:

The ornamental design for an automobile visor rate sign, or article of similar nature, as shown.

In testimony whereof, we affix our signatures.

PHILIP L. DAVIS.
JULIAN J. RAPHAEL.
